UNITED STATES PATENT OFFICE.

THOMAS J. HUBBARD AND WILLIAM W. HUBBARD, OF LAMOILLE,
ILLINOIS.

WASHBOARD.

No. 798,793.

Specification of Letters Patent.

Patented Sept. 5, 1905.

Application filed July 31, 1902. Serial No. 117,890.

To all whom it may concern:

Be it known that we, THOMAS J. HUBBARD and WILLIAM W. HUBBARD, citizens of the United States, residing at Lamoille, in the 5 county of Bureau and State of Illinois, have invented a new and useful Washboard, of which the following is a specification.

This invention relates to improvements in washboards.

10 The object of the present invention is to improve the construction of washboards and to provide a rubbing-surface adapted for washboards and washing-machines and capable of holding a quantity of soap and of dispensing 15 or applying the same to the clothes or other fabrics during the operation of washing.

A further object of the invention is to provide a rubbing-surface of this character which 20 will enable clothes to be rapidly and thoroughly washed without injuring the fabrics and without tearing the buttons therefrom.

The invention consists in the construction and novel combination and arrangement of parts hereinafter fully described, illustrated 25 in the accompanying drawings, and pointed out in the claim hereto appended.

In the drawings, Figure 1 is an elevation of a washboard provided with a rubbing-surface constructed in accordance with this invention. Fig. 2 is a detail perspective view 30 of one of the rolls. Fig. 3 is a transverse sectional view of the same.

Corresponding parts in the several figures are indicated by similar numerals of reference.

35 1 designates the frame of the washboard, having side bars provided at intervals with bearings for the reception of the journals 3. Each roll is provided at suitable intervals with longitudinal grooves 5, dividing the roll into 40 longitudinal ribs or portions 6, lying between the longitudinal grooves and provided with transverse corrugations 7. The longitudinal grooves 5 may be of any desired depth, provided that they are deeper than the transverse 45 grooves or corrugations of the ribs or portions 6. The side walls of the grooves 5 are approximately parallel to each other, and they are adapted especially for the purpose of receiving, holding, and dispensing soap, 50 which is to be supplied to the said grooves prior to the operation of washing and dispensed during the operation of washing to the clothes or fabrics that are being operated upon. If the side walls of the grooves 9 were

permitted to diverge outwardly, the said 55 grooves would obviously be rendered unfit for the purpose of holding and dispensing soap, which is the sole reason for their presence. The transverse grooves or corrugations 7 are 60 arranged at a pitch to form threads for feeding the clothes laterally, and the transverse grooves or corrugations of the alternate rollers are reversely arranged to provide right and left hand screw-threads, the tendency of the adjacent rollers being to move the clothes 65 or other fabrics in opposite directions, and by this construction the clothes will be thoroughly rubbed and at the same time supplied with soap from the dispensing-grooves 5. It is obviously important that the grooves or 70 corrugations 7 be spirally disposed in order that the materials rubbed over the rollers may receive a lateral feed motion with relation to the longitudinal soap-dispensing grooves in order that the contents of the latter may be 75 evenly and perfectly distributed upon the goods that are to be washed. The soap may be supplied to the said grooves and packed therein prior to the operation of washing in any suitable convenient manner. The rollers 80 are spaced apart to permit water to pass readily between them, so that the water expelled from the clothes will run through the washboard. The latter for the same reason may be 85 thoroughly and quickly dried after the operation of washing has been completed.

The improved rubbing-surface, which has been herein described, is applicable to washing-machines of various constructions, as will 90 be readily understood.

It will be seen that the rubbing-surface is simple and inexpensive in construction, and that it is capable of enabling clothes to be rapidly and thoroughly cleansed without injury, and that the longitudinal grooves 5 are 95 adapted to hold a quantity of soap and to dispense the same to the clothes or other fabrics during the operation of washing. It will be clear that during the operation of washing, owing to the alternate opposite pitch of the 100 grooves or corrugations 7, the clothes rubbed over the rollers will partake of a zigzag movement, whereby they are moved slightly in a longitudinal direction with relation to the roller or parallel to the axis of the latter, 105 thereby causing the soap contained in the longitudinal grooves 5 to contact with and to be dispensed or deposited upon the clothes in

sufficient quantity to enable the cleansing of the clothes to be thoroughly and expeditiously performed. The grooves 5 are in no sense to be considered as corrugations for the purpose 5 of increasing the rubbing qualities of the washboard. On the contrary, the said grooves are to be filled with soap, which is to be packed therein prior to the commencement of the laundering operation, the quantity of 10 soap deposited in said grooves being intended to suffice for an entire "washing" unless an unusually large quantity of clothes are to be laundered.

We are aware that in various forms of 15 washing-machines and washboards rubbing-surfaces have been formed of spirally-grooved rollers.

We are also aware that rollers utilized for 20 rubbing purposes in washing-machines have been annularly grooved and provided with intersecting longitudinal grooves.

We are not aware that a rubbing-surface 25 in a washboard or a washing-machine has ever been formed by a plurality of spirally-grooved rollers, each of said rollers being

provided with longitudinal grooves of distinctly greater depth than the spiral grooves which are intersected thereby, said longitudinal grooves being for the definite purpose of receiving and dispensing soap to the fabrics operated upon during the operation of washing.

We claim—

A rubbing-surface for clothes-washing machines including a plurality of rollers mounted 35 for rotation adjacent to each other, each of said rollers being spirally grooved, and provided with longitudinal soap-dispensing grooves having parallel side walls and of greater depth than the spiral grooves intersected thereby.

In testimony that we claim the foregoing as our own we have hereto affixed our signatures in the presence of two witnesses:

THOMAS J. HUBBARD.
WILLIAM W. HUBBARD.
